UNITED STATES PATENT OFFICE.

CHARLES H. WILSON, OF COLUMBUS, OHIO, ASSIGNOR TO THE WESTERN ELECTRIC COMPANY, OF CHICAGO, ILLINOIS.

LIGHTNING-ARRESTER.

SPECIFICATION forming part of Letters Patent No. 399,305, dated March 12, 1889.

Application filed November 19, 1887. Serial No. 255,593. (No model.)

To all whom it may concern:

Be it known that I, CHARLES H. WILSON, a citizen of the United States, residing at Columbus, in the county of Franklin and State 5 of Ohio, have invented a certain new and useful Improvement in Lightning-Arresters, of which the following is a full, clear, concise, and exact description, reference being had to the accompanying drawings, forming 10 a part of this specification.

My invention relates to lightning-arresters; and it consists in two springs placed over metal plates, the two springs being connected by a fusible wire supported upon a bead upon 15 a frame or base in such manner that the springs are normally suspended above the underlying metal plates, respectively, one of which plates connects electrically direct to the ground, while the other connects with a 20 return-wire extending through a galvanometer, annunciator, or other indicating device and battery or generator to the line-wire or direct to ground. When a strong current is sent through the connecting-wire, it is fused 25 or elongated, and the springs by their own tension are brought against their respective metal plates.

My invention also relates to a galvanometer or indicating apparatus, by means of which 30 it may be determined when the wire of a lightning-arrestor has been fused or elongated.

My invention is specially designed for use in telephone-exchanges, but may be employed in connection with telegraph, district, or other 35 wires. The line coming in is connected with one of the springs, and thence the circuit may be traced through the fusible wire and the other spring and the wire of the cable leading to the switch upon the switch-board, and 40 thence through the switch and an annunciator or other apparatus to ground in the usual manner. The lightning-arresters may be arranged side by side upon a common base, which may be placed in the tower or in the 45 terminal boxes upon poles. The base is preferably provided with a bead, on the opposite sides of which are placed metal plates. The fusible wire passing over this bead rests, preferably, in the slot of a metallic screw, 50 the object of the screw being to prevent the fusible wire, when heated, from sinking into

the wood and to make more certain the fusing of the wire. The springs are held by their connecting fusible wires passing over the bead out of contact with the metal plates. When 55 a wire is fused or elongated, its springs close upon the underlying metal plates. The line is thus closed to ground, and at the same time the office portion of the line by a separate connection forms a complete local circuit. By 60 means of a battery and galvanometer, either permanently or temporarily placed in the circuit with the metal strip, it may be readily determined when a wire is fused or elongated. As there are many springs over each plate, it 65 is readily determined which particular circuit has been interrupted by the falling of the drop or signal of the particular line.

My invention is illustrated in the accompanying drawings, in which—

Figure 1 is a perspective view showing the base provided with two lightning-arresters embodying my invention. Fig. 2 is a diagram illustrative of the circuits.

The base *a* may be of wood, and is provided 75 with a bead or strip, *b*, in which are inserted the screws *x*. The metal plates *c d* are placed on opposite sides of the bead, as shown, the block being preferably cut away or grooved, as shown, to afford room for the metal plates. 80 The circuit-wire *e* is connected with the spring *f* of the lightning-arrestor, and its normal circuit may be traced thence through the fusible wire *g* to the other spring, *h*, and thence by wire *i*, which may be a wire of a cable, to the 85 usual spring-jack, *k*, and thence through an- nunciator *l* to ground. The fusible connect- ing-wire *g* may be of lead or German silver or any fusible metal, and must be of sufficient resistance to be fused when current of undue 90 strength is sent over the wire. The springs *f h* are so adjusted that when the connecting- wire *g* is broken they will close upon metal plates *c d*, respectively. The spring *f* is made so as to possess less tension than the spring 95 *h*, in order to insure against the former mak- ing contact with the underlying plate with- out the spring *h* making contact with the plate underlying the latter. Any line *e* is thus automatically connected to ground by 100 the closing of its spring upon plate *c*. Wire *i*, which leads to the switch-board or to ground,

is also closed at the same time when spring *h* closes upon plate *d*. Between strip *d* and its ground I provide a galvanometer or indicating device and battery, as shown, so that 5 when spring *h* closes upon strip *d* the fact will be indicated by such indicating device, and the local circuit having been completed through the wire *i*, spring-jack *k*, and annunciator *l*, the latter falls and indicates the particular line interrupted, the galvanometer or indicating device indicating the particular location of any series of lightning-arresters.

Having thus described my invention, I claim as new and desire to secure by Letters Patent—

15 1. The combination, with the base *a*, provided with the bead *b*, of lightning - arrester springs arranged in rows on opposite sides of said bead and suspended by fusible wires passing over the bead, and common ground connections or strips *c d*, substantially as described.

20 2. In a lightning-arrester, the springs *f h*,

connected together and suspended by a fusible wire passing over a screw-head, *g*, in combination with the underlying contact-pieces *c 25 d*, the tension of spring *h* being greater than the tension of spring *f*, to insure the closing of spring *h* upon its underlying connecting-piece *d* when the connecting-wire is fused or elongated, substantially as described. 30

3. In a lightning-arrester, the combination, with springs adjusted to press toward underlying contact-strips, in combination with said contact-strips, an insulating-piece separating said strips, and a fusible wire connecting said springs and passing over said insulating-piece to hold said springs normally suspended, substantially as described. 35

In witness whereof I hereunto subscribe my name this 19th day of September, A. D. 1887. 40
CHARLES H. WILSON.
